ELECTRIC FURNACE

August L. Weyhing, Louisville, Ky., assignor to
Edmund A. Steinbock, Louisville, Ky.

Application February 14, 1940, Serial No. 318,900

1 Claim. (Cl. 219—36)

This invention relates to improvements in furnaces, and particularly electric furnaces.

The furnace of this invention was developed primarily for use in small production laboratories such as dental laboratories and the like, which are usually located in office buildings and other locations where draft chimneys or stacks are not available and cannot be readily constructed. Another use for these furnaces is where a relatively small and portable furnace is desirable or necessary, since they may necessarily be shifted from position to position.

It is one of the chief objects of this invention to provide a furnace from which the fumes and products of elimination caused during operation of the furnace can be readily and completely disposed of without contaminating the atmosphere of the room in which the furnace is used.

Another object of this invention is the provision of an electric furnace which must generate a relatively high heat and in which deleterious gases are generated and prevented from attacking the heating elements.

Another object of this invention is the provision of means in a furnace which is used for burning out wax from molds to prevent the wax from interfering with or breaking down the heating elements.

A still further object of this invention is the provision of an electric furnace for heating molds made of investment compositions and in which a neutral or oxidizing atmosphere is maintained to avoid breaking down of the mold.

A still further object of this invention is the provision of a furnace in which gas or the like may be introduced during its operation, or in which a partial or semi-vacuum may be established, depending upon the content of the furnace and the result desired.

Other objects and advantages of the present invention should be readily understood by reference to the following specification when considered in connection with the accompanying drawings and forming a part thereof, and it is to be understood that any modifications may be made in the exact structural details therein shown, without departing from or exceeding the spirit of the invention as defined by the appended claim.

In the drawings:

Fig. 1 is a front elevation of an electric furnace embodying the improvements of this invention.

Fig. 2 is a side elevation of the furnace shown in Fig. 1, as seen from the right hand side thereof, parts being broken away to clearly illustrate the interior construction of the furnace.

Fig. 3 is a rear, elevational view of the furnace as shown in Fig. 1.

Fig. 4 is an enlarged, fragmentary, vertical, sectional view taken on line 4—4 of Fig. 3.

Fig. 5 is an enlarged, vertical, sectional view taken at right angles of Fig. 4, on line 5—5 of Fig. 2.

Fig. 6 is an enlarged, fragmentary, horizontal, 5 sectional view taken on line 6—6 of Fig. 3.

Fig. 7 is an enlarged, vertical, sectional view, taken on line 7—7 of Fig. 3.

Throughout the several views of the drawings, similar reference characters are employed to denote the same or similar parts.

As was noted above, this furnace was primarily developed for use in dental laboratories and similar places for the burning out and heating of molds made from investment compositions and 15 which laboratories are generally situated in office buildings, where access to exhaust stacks and the like are impossible. As is well known, metals, whether in the pure state or alloyed, have considerable shrinkage when cooling from the fluid state to the solid state after being cast. In dental work, and when using a gold alloy as bridges, fillings, plates, and the like, a linear shrinkage of 1.25% is the rule. To overcome this shrinkage, the mold investment composition is composed 20 generally of some form of plaster, a filler, a time setting element and a thermal expanding agent, together with other ingredients to provide the mold with certain characteristics. The mold has embedded therein a wax pattern made accurately 25 to the size and shape of the dental part to be made. The mold is placed in a furnace and heated first to dissipate the wax pattern by melting and burning, and then the mold is heated to cause the thermal expansion agent to expand the cavity left by the disappearing wax pattern an amount equal to the metal shrinkage upon cooling 30 from the fluid state to the solid state. As can readily be appreciated, the melting wax would normally flow onto the heating element embedding 35 surface, which is more or less porous, and would find its way to the heating elements themselves, and in a short time damage said elements. At the same time, the constituents of the mold, 40 during the thermal expansion thereof, give off gases which may be deleterious to the heating elements and to the membranes of the head and throat, if not downright poisonous to life itself, 45 would permeate the laboratory room if not properly and completely exhausted from the furnace 50 to the atmosphere.

It has been found that a furnace, without the improvements disclosed in this application, burned out in five runs, where the furnace had been 55 heated up to 1300° F. for gold alloy castings and to 1700° for stainless steel castings; that is, the heating elements were destroyed to the extent that the furnace was useless, while, with the improvements of this application, the furnace was 60 operated continuously for months without in

anywise a noticeable decrease in operation and efficiency of the heating elements.

Referring specifically to the drawings, the furnace of this invention comprises a front frame 10 having angle iron cross section sides and top from which project legs 11 and 12. Opposed to the front frame 10 is a rear frame 13, similar in all respects to the front frame 10 and having depending rear legs 14 and 15. A sheet metal housing 16 extends between the front and rear frames 10 and 13, and comprises a top 17 and opposing sides 18. The sides 18 are joined by means of a sheet metal tray 19 at a point just above the end frame legs. The top, sides and bottom of the furnace are similarly constructed and comprise a first layer 20 of heat-insulating material, a second layer 21 of heat insulating material and a final inner lining 22 of refractory material. These several layers are formed initially in blocks or slabs and supported one on another with the inner liners interlocking and forming the supports for the whole and the proper spacing of the inner cavity top, bottom and side walls. The front wall 23 and rear wall 24 are similarly constructed and likewise made up of preformed elements, the outermost 24a being compressed asbestos material in such a manner as to provide a slate like outer surface, and which contacts the end edges of the outermost insulation layer 20. Behind the outermost layer 24a is a layer 25 of heat refractory material, such as fire brick, which contacts the edges of the second heat insulating layer 21 and the inner refractory liner 22. The front wall 23 has its layers 24a and 25 provided with a rectangular opening 26 which aligns with the inner surfaces of the inner liner 22 and provides an opening to the furnace muffle chamber.

The opening 26 in the front wall of the furnace is closed by the usual swinging door 27, which, as usual, comprises an outer sheet metal casing 28 with a suitable heat resisting material 29 filling. Secured to the lower ends of the door sides are arms 30 having apertures below, through which passes an axle bar 31. The axle bar 31 is secured in the door arm bearings by any suitable means and the axle bar passes through apertures formed in angle iron brackets 32 and 33 which have their opposite ends respectively secured to the front frame 10. The axle bar 30 projects to one side of the furnace proper and has secured thereto or integral therewith a counterweight 34 employed to hold the door in the closed position, as illustrated in the drawings. The door, however, may be opened or positioned at right angles to that illustrated in solid lines in the drawings, and this position is illustrated by dot and dash lines in Fig. 2, and identified by reference character 35. In order to maintain the door in its open position, use is made of an abutment plate 36 which conveniently takes the form of a short piece of angle iron, suitably secured to the front of the furnace.

The inner linings 22 of the furnace proper or the muffle, as noted above, are of refractory material, and they have secured or embedded therein the heating wires or elements, and these elements have their ends projecting from the rear end of the linings. These projecting ends, indicated by reference character 37, project through the rear wall 24 of the furnace. By this construction, adjacent sides of the muffle liners 22 have their heating elements exteriorly of the furnace adjacent one another and are connected by a suitable connector 38. By this

construction, the heating element of each muffle side or furnace liner is connected in series electrically with its adjacent member heating elements.

5 The space below the furnace bottom plate 19 and between the supporting legs 11, 12, 14 and 15 forms a compartment in which is located a rheostat for controlling the current flow to the heating elements. As seen in Fig. 2, the furnace sides 18 extend below the bottom plate 19 to form sides for the rheostat compartment, while the front of this compartment is formed by a plate 39 suitably secured to an inner surface of the front leg front flanges. Projecting through 10 the front 39 is a shaft 40 carrying exteriorly of the plate 39 a knob 41. Within the rheostat compartment 42, the shaft 40 is journaled in a bracket 43 and has secured thereto a bevel gear or pinion 44 meshing with a gear or pinion 45 carried by the rheostat shaft 46. The shaft 46, as is usual, is journaled in the rheostat casing 47 and carries a movable control arm 48 which is adapted to pass over the resistance buttons (not shown) which have the electrical resistance connected therewith. The rheostat casing 47 is secured to the undersurface of the furnace bottom 19 in any suitable manner, such, for example, as by straps or arms 49.

30 The rheostat has the usual contact supporting plate 50 for binding posts 51 and 52 which are respectively connected with the resistance buttons and the movable contact. As seen in Fig. 3, the binding post 51 is connected by wires 53 with one of the heating element connectors 38, while the other contact 52 is connected by a wire 54 with a binding post 55 carried by the furnace back wall, and which binding post 55 may be connected behind the back wall plate 24 with a second binding post 56 to which is connected wire 57 leading from a suitable electric source or commercial voltage. The second wire 58 of the electric source or commercial voltage is connected by means of wire 59 with another heating element connector 38. As will be readily seen, this wiring makes a complete electrical circuit from the electric source or commercial voltage, by way of wire 57 to wire 54, rheostat, wires 53, heating elements and their connectors to wire 59 and wire 58 back to the electrical source or commercial voltage.

50 The back wall 24 of the furnace is provided with an aperture 60 located substantially centrally of the width of the muffle chamber and substantially at the top of the vertical height thereof. Secured to the outer surface of the back wall 24 is an apertured member 61 which conveniently takes the form of a standard pipe flange and having a central threaded aperture in axial alignment with the aperture 60 in the back wall 24. Threaded into the pipe flange 61 is a nipple 62 which has its other end threaded into a pipe T 63. Extending from the upper side of the T 63 is a pipe 64 which, as will later be made clear, is the exhaust pipe for the furnace. The lower side of the T 63 has threaded thereinto a plug 65 which is centrally bored or apertured, as at 66. It might be noted at this time that the aperture 66 provides a drain for the moisture drawn into the exhaust pipe 64 and that the exhaust pipe 64, which is nothing more than ordinary iron pipe, extends to a suitable point in the wall of the building or room, such as a window, where it is projected into the atmosphere for dissipated gases and the like. Let into the T member 63, through one side thereof, at the uppermost point

above the aperture 60, is a tube 67 having its inner end 68 upwardly disposed into the exhaust pipe 64. In order to secure the exhaust pipe 68 in the side of the T 63, use may be conveniently made of the usual tubing connection 69. The other end of the tubing 67 is connected to one side of a T 70, the other end of which T 70 is connected by a piece of tubing 71 with an air pressure gauge 72. The third opening of the T 70 has connected therewith one end of a tube 73, the other end of which is connected to an adjustable air control valve 74. The air control valve 74 has its other side connected with a pipe 75 which extends from an air pressure generator, tank or the like.

The air control valve 74 may be of any convenient or desirable form, one such valve being shown, in Fig. 6, and comprising a valve body 76 provided with a valve seat 77 with which a needle point 78 co-operates. The needle point valve 78 has a threaded stem 79 projecting therefrom and passing through a packing nut 80 carried by the valve body 76. The outer end of the valve stem 79 has secured thereto knob 81 by which the valve is adjustable.

The valve 74 is disposed behind an instrument panel 82 which is secured to and upstands from the rear end of the furnace top 17.

Any suitable means may be employed for positioning the valve that shown including a short metal strap 83 through which the air supply pipe 75 passes and is welded as by welds 84. One end of the strap 83 is provided with a threaded aperture through which a screw 85 passes for clamping thereto a flange 86 rearwardly projecting from one lateral side of the instrument panel 82. It should be noted that the air pressure gauge 72 is secured to the panel 82 and is conveniently located adjacent the air regulating valve 74 so that the pressure in the tube 68 can be readily determined and adjusted.

Formed through the rear wall 24 of the furnace at one of the upper corners of the muffle chamber is a second aperture 87 in which is disposed a thermocouple 88. In order to protect the thermocouple, it is encased in a substantially non-porous refractory covering 89 which has its inner end closed as at 90 and its outer end open to permit the ends of the thermocouple to project therefrom. The thermocouple is a continuous wire member bent in the middle and having its ends outwardly of the rear of the furnace. Said rear ends of the thermocouple will bend downwardly parallel with the back of the furnace and are respectively indicated by reference numerals 91 and 92, respectively connected with binding posts 93 and 94 carried by the furnace back wall. The binding posts 93 and 94 are respectively connected by wires 95 and 96 with binding posts at opposite sides of a pyrometer 98 carried by the instrument panel 82.

In order that the air gauge and pyrometer may be readily read, the forward face of the instrument panel 82 carries a suitable light 99 arranged to direct its rays onto the dials of the said pyrometer and air gauge.

In operation, the exhaust pipe 64 is connected to atmosphere while the pressure pipe 75 is connected to an air pressure generator or pressure tank. The electric wires 57 and 58 are connected with an electric source for heating the heating elements surrounding the muffle chamber. The

air valve 74 is opened to permit an air flow through the tubes 73 and 67 into and through the exhaust pipe 64. Depending upon conditions, the air valve 74 is more or less opened and the pressure within the tubes 73 and 67 determined by the pressure gauge 72, which measures the pressure in the tubes 73 and 67. The flow of pressure out of the tube 67 by way of the nozzle 69 creates a vacuum therebelow and draws the atmosphere within the muffle chamber through the aperture 60 and nipple 62 into the exhaust pipe 64 and forces same out to the atmosphere. To prevent the creation of a vacuum in the muffle chamber, the door 35 is provided with a pair of apertures 10 or openings 100 and these permit a continuous supply of fresh air to the furnace, thereby providing a neutralizing or oxydizing atmosphere to develop in the furnace muffle chamber. At the same time, should it be desired to pass some other gas into the muffle chamber besides fresh air, this may be done by supplying same through the openings 100 and having it drawn into and through the furnace chamber.

As is usual, it may be desired to vary the temperature within the furnace, from a point at or below 1250° F., the usual low point for gold alloy castings, to a point of 1700 or 1800° F., the usual high point of standard stainless steel alloy castings, and for which purpose the rheostat 47 is adjustable by the knob 41. The temperature of the furnace cavity is at all times available on the pyrometer 98 through the thermocouple 88.

As was mentioned above, the furnace is used, first to melt out the wax pattern in the mold and in order to prevent this molten wax from contacting the heating elements in the furnace bottom inner liner 21, there is placed within the furnace a removable metal tray 101.

From the foregoing, it will now be appreciated that there has been provided an electric furnace primarily for use in dental laboratories and the like, which adequately meets the objects initially set forth above.

What is claimed is:

In an electric furnace of the class described, including an inclosing metallic shell, a muffle substantially centrally of the shell, heat insulating lining between the shell and muffle and filling the space therebetween, a heating element associated with the muffle, means for controlling the current flow to the heating element, said muffle chamber having its one end open and its other end insulated by the lining from the shell back wall, pressure exhaust means connected with the muffle chamber through the back wall for exhausting gases and moisture from the muffle chamber, including an opening through the back wall, a nipple carried by said back wall in line with the opening therein, an exhaust pipe connecting the nipple to the atmosphere, and a tube connecting a pressure source with the exhaust pipe at a point above the nipple for causing forced draft through the exhaust pipe, a valve carried by the shell for regulating the flow of the pressure through the tube and thereby regulating the force of the exhaust draft and a gauge for indicating the pressure flow through the tube into and through the exhaust pipe.
